UNITED STATES PATENT OFFICE

WILLIAM C. PFEIFFER, OF DAYTON, OHIO, ASSIGNOR TO THE EGRY REGISTER COMPANY, OF DAYTON, OHIO, A CORPORATION OF OHIO

AUTOGRAPHIC REGISTER

Application filed April 4, 1932, Serial No. 602,927, and in Canada April 4, 1932.

My invention relates to autographic registers.

It is the object of my invention to provide means of time stamping the autographic register stationery prior to its being ejected from the machine or stored in the machine, and by the act of stamping the stationery with the time stamp, initiating the ejection of the stationery so stamped, and to prevent any further stationery being ejected until the stamping mechanism is again operated.

It is my object to provide an autographic register operated by an electric motor having a switch which is set for operation by the downward movement of the stamping mechanism, the setting of which will be completed upon the impact of the time stamp with the stationery of the autographic register and the return upwardly of the time stamp, whereupon the movement of the time stamp having set the switch mechanism for the operation of the register upon the return of the time stamp to its initial position, the switch can close the circuit and the motor will eject the sheets that have been stamped, but no further sheets.

Referring to the drawings, Figure 1 is a front elevation of the register and the time stamp.

Figure 2 is a side elevation from the motor and switch side.

Figure 3 is a section on the line 3—3 of Figure 7.

Figure 4 is a section on the line 4—4 of Figure 2.

Figure 5 is a diagrammatic view of the main current switch, the motor, and the autographic register switch.

Figure 6 is an elevation of the driving mechanism for ejecting the sheets, being a section on the line 6—6 of Figure 4.

Figure 7 is a side elevation of the switch mechanism in a position of rest.

Figure 8 is a similar view showing the mechanism at the beginning of a cycle of operations.

Figure 9 is a similar view showing the mechanism as it appears during operation.

Figure 10 is an inside elevation of the ratchet and pawl and switch arm mechanism

showing the parts in position as in Figure 7.

Figure 11 is a similar view showing the parts as in position in Figure 9.

Referring to the drawings in detail, 1 is an autographic register. 2 indicates the time stamp mechanism hinged at 3 on the bracket 4. It is provided with a depending arm 5 to which is connected a spring 6 anchored on the register at 7 and to which is also connected the spring 8 connected to the register at 9. 55 Pivoted to the arm of the time stamp at 10 is a Bowden wire 11 moving within its guiding sheave 12 which extends through the bottom of the register and makes its exit at 13 where the wire is connected at 14 to the 60 lever 16. The switch lever 16 is so arranged that it will be actuated after the time stamp has engaged the surface of the paper in the autographic register as at 17. This is brought about by the closing of the contacts 70 18 and 19, which remain closed until broken by the switch as hereinafter described as the switch passes through a cycle of operations. The closing of the switch members 18 and 19 closes the circuit to the motor 20 which 75 drives the worm 21, worm wheel 22, shaft 23, gear 24, gear 25, shaft 26, gear 27, idler gear 27a, gear 28 on ejecting roll 29 and gear 30 on ejecting roll 31. These gears eject the paper sheets 32 in the usual manner which 80 have been stamped by the time stamp 2.

The motor 20 is supplied with power from the main power lines 33 and 34 which are controlled by the switch 35. These lines pass through cable 36 to the switch contacts 18 and 19 so as to control the flow of current through the wires 37 and 38 which lead directly to the motor 20.

The operation of the switch is as follows:

It will be noted that the driving gear 22 is 85 loosely mounted upon the shaft 23 and that it is necessary to effect a connection between the gear 22 and shaft 23 by an interlocking switch mechanism which will be synchronized with the movement of the time stamp. 90 The time stamp is so arranged that when it is brought down and stamps the paper sheets such as 32, and then moves upwardly out of engagement with the sheets, the circuit will be closed and the worm 21 and worm gear 22 100

connected to the shaft 23 so that the motor can drive the shaft 23 through a cycle of operations until the tickets on the sheets 32 can be ejected, whereupon the motor will 5 come to rest and lock it against further forward movement. This necessitates the stamping of each ticket because unless so stamped the machine cannot be operated either by the motor or by the hand operated 10 handle, which will be hereinafter described.

Accordingly, when the Bowden wire 11 starts from the position shown in Figures 1 and 7, the switch lever 16 is down and the contacts 18 and 19 are open. The sheets are 15 unstamped and the machine is at rest. The downward movement to stamping position of the time stamp 2 results in moving the lever 16 to a horizontal position, which is a setting position. The result of this movement is to 20 permit the release of the bell crank member 39 off of the pin 40 on the disk 41. This bell crank member is pivoted at 42 upon the lever 16 and is actuated by a spring 43. The upper end of the bell crank lever is formed with a 25 hook 44 which is permitted to engage over the top of the lever 45 when the actuation lever 16 moves to horizontal position. This occurs under the influence of the spring 43. On the 30 end of the lever 45 is pivoted a finger 46 pulled to the left hand by the spring 47. This finger 46 in rest position rests within the notch 48 of the disk 41. It overlies a cam nose 49 on the lever 45. The upper surface 35 of the lever 45 has a shoulder 50 which presses the contact member 18. When the time stamp 2 returns to its elevated position, it carries with it the lever 45 by reason of the action of the hook 44, thus elevating the member 46 and the nose 49. The spring 47 pulls 40 the member 46 on top of the margin of the disk 41 so as to guide the nose 49 into similar engaging position so that the two members will ride together on top of the margin of the disk 41. When they do so, they serve to 45 permit the connection of the disk 41 to the gear 22. On the gear 22 is a ratchet 22a engageable by a pawl 51 pivoted at 52 on the disk 41 and limited in its outward movement by the pin 53. This pawl is moved inwardly 50 by the spring 54 connected to the disk 41 at 55 and to the pin 56 through the slot 57 in the disk 41.

Thus the pawl 51 is spring pressed into engagement with the ratchet 22a to connect 55 the shaft 23 on which the disk 41 is pinned by the pin 41a to the driving gear 22. The action of the pawl 51 is controlled by the lever 58 pivoted at 59 on the disk 41 which has a hook 60 that is not free to operate so long as 60 the nose 49 retains it in inoperative position, which in turn retains the pawl 51 in inoperative position with respect to the ratchet 22a. But upon lifting of the nose 49 the parts 65 can be connected together and the motor can drive the shaft 23 through a cycle of opera-

tions until the notch 48 again comes beneath the members 46 and 49, permitting them to drop down into inoperative position under the influence of the spring 49a. This disconnects the motor and its driven gears 21 and 22 from the shaft 23. It is impossible to operate the machine without again stamping the next set of sheets 32.

In the event it is desired to operate the machine by hand instead of by electric power, 75 the handle 61 can be employed, but it likewise will be locked against movement until the mechanism is unlocked and interlocked by the action of the time stamp 2 as heretofore described, whereupon the sheets can be ejected 80 by a single cycle of operations, after which they will be again locked against further movement until there is another actuation of the time stamp.

It will be understood that I desire to comprehend within my invention such modifications as may be necessary to adapt it to varying conditions and uses.

Having thus fully described my invention, what I claim as new and desire to secure by 90 Letters Patent, is:

1. In combination, an autographic register, means of ejecting sheets therefrom, and a time stamp adapted to stamp the sheets in the register and means connected therewith for 95 unlocking said register and means connected to said unlocking means for causing the ejection of the sheets so stamped.

2. In combination, an autographic register, a time stamp, means for ejecting sheets from 100 said register, an electric motor therefor, an electric switch controlling said motor, and means connected to said time stamp for actuating said switch in accordance with the operation of the time stamp.

3. In combination, an autographic register, a time stamp, means for ejecting sheets from 105 said register, an electric motor therefor, an electric switch controlling said motor, and means connected to said time stamp for actuating said switch in accordance with the operation of the time stamp, and yielding means 110 for returning said time stamp to its initial position with its actuating means.

4. In combination, an autographic register having a plurality of sheets, means for ejecting said sheets, a time stamp for stamping said sheets, a motor for driving said ejecting means, a switch for said motor operable by 115 said time stamp whereby when the stamp is applied the switch is closed and the motor runs through a cycle of operations to eject the sheets, stamp, and the switch opens at the end of the ejecting movement.

5. In combination, an autographic register 120 having a plurality of sheets, means for ejecting said sheets, a time stamp for stamping said sheets, a motor for driving said ejecting means, a switch for said motor operable by said time stamp whereby when the stamp is 125

130

applied the switch is closed and the motor runs through a cycle of operations to eject the sheets, means to open the switch at the end of the ejecting movement, and means for locking said actuating mechanism against further movement until initiated by another stamping operation of the time stamp.

6. In an autographic register, means to eject a sheet of paper, a motor for operating 10 said means, a time stamp for stamping said sheet, said stamp being operatively connected to the motor for starting it, and means operated by the motor for stopping the motor after a definite period of operation.

15 7. In an autographic register, means for ejecting a sheet of paper, a shaft operatively connected to said means, a gear loosely mounted on said shaft, and means operating under one condition to cause the gear to rotate and to lock the shaft to the gear and under another condition to lock the shaft 20 against rotation and to release the gear from the shaft.

8. In an autographic register, means for 25 ejecting a sheet of paper, a shaft operatively connected to said means, a gear loosely mounted on said shaft, a motor for rotating said gear, a switch for starting and stopping said motor, and means adapted in one position to close the switch and to cause the gear to be connected to the shaft and in another position to open the switch and to disconnect the gear from the shaft.

9. In an autographic register, means to 35 eject a sheet of paper, a time stamp for stamping said sheet, a shaft operatively connected to said means, a gear loosely mounted on said shaft, and means operated by the time stamp and operating under one condition to cause 40 the gear to rotate the shaft and to lock the shaft to the gear and under another condition to lock the shaft against rotation and to release the gear from the shaft.

10. In an autographic register, means to 45 eject a sheet of paper, a time stamp for stamping said sheet, a shaft operatively connected to said means, a gear loosely mounted on said shaft, a motor for rotating said gear, a switch for starting and stopping said motor, and 50 means operated by the time stamp and adapted in one position to close the switch and to cause the gear to be connected to the shaft and in another position to open the switch and disconnect the gear from the shaft.

55 In testimony whereof, I affix my signature.

WILLIAM C. PFEIFFER.
